Application November 24, 1945, Serial No. 630,666

13 Claims. (Cl. 260—594)

1

This invention relates to aldol-type condensations and more particularly to the condensation of formaldehyde with aliphatic ketones and nitroparaffins.

This condensation is well known to the art, but a great deal of difficulty has been experienced in the production of monomethylol reaction products. It was originally thought, for instance, that acetone and formaldehyde condensed to form 3-ketobutanol in high yields, but subsequent investigations have demonstrated that the condensation was far more complex than first described. Actually, it has recently been established that at least five products result from this condensation and that the large number of by-products limits the yield of 3-ketobutanol to about 27%. This fact is in contrast to the yields shown for various prior art procedures which claimed to increase the yield of 3-ketobutanol by increasing the ratio of acetone to formaldehyde and by controlling the pH of the reaction mixture. The high yields previously recorded were undoubtedly due to the presence of large amounts of secondary products which were not separated from the 3-ketobutanol and which were, therefore, unknowingly considered as 3-ketobutanol itself. Although the condensation of acetone and formaldehyde has been discussed specifically, the same situation exists generally in the condensation of formaldehyde with other aliphatic ketones and also with nitroparaffins.

Now, in accordance with this invention it has been found that formaldehyde may be condensed with a liquid organic compound selected from the group consisting of aliphatic ketones and nitroparaffins by refluxing the aliphatic ketone or nitroparaffin in a fractionating column below the column flood point while simultaneously passing formaldehyde and an alkaline catalyst downward through the column. The process operates on the principle of true countercurrent action of the reactants and the column functions in the dual capacity of a reaction tower and a fractionating column.

In practicing the process in accordance with this invention, acetone and formaldehyde, for example, may be condensed to give high yields of 3-ketobutanol by refluxing the acetone in a fractionating column, operating the column below its flood point while simultaneously adding Formalin, adjusted to a pH of about 10 with aqueous sodium hydroxide, at the top of the column. The Formalin feed entering the top of the packed column is accurately metered and this, in conjunction with operation of the column

2

below its flood point permits control of the relative proportions of the acetone and formaldehyde so that at the top of the column the formaldehyde concentration is highest and the concentration of 3-ketobutanol is least. Due to the combined effect of the chemical reaction and the rectifying action of the column, the 3-ketobutanol is rapidly removed from the main reaction zone at the top of the column and the reflux becomes progressively richer in 3-ketobutanol content and leaner in formaldehyde as it descends through the column. The formation of secondary products is in this way hindered. Upon completion of the condensation the water and excess acetone are removed from the crude reaction mixture by distillation at reduced pressure, and fractionation of the residue results in a high yield of 3-ketobutanol.

Figures 1 and 2 in the accompanying drawings illustrate apparatus and procedures by which the process of this invention may be carried out. The apparatus shown in Figure 1 is for the batch method of producing the monomethylol reaction products. Storage tanks 1, 2, 3 and 4 contain the reactants and reagents used in the process; namely, the alkaline catalyst solution, the formaldehyde solution, the ketone or nitroparaffin, and the solution of acidic material used to neutralize any alkaline catalyst reaching heating pot 9.

The alkaline catalyst and formaldehyde solutions are blended by means of the plate mixer 5, passed through pH control 6, in which the pH of the alkaline solution is determined at regular intervals, and then through metering valve 7 into the top of fractionating column 10. The ketone or nitroparaffin may either be charged into heating pot 9 or passed through metering valve 8 into the top of fractionating column 10, although only the former procedure is necessary in the event a batch technique is utilized. As will be shown in the examples, however, it often is desirable to charge heating pot 9 with a portion of the ketone or nitroparaffin and later add additional amounts of either of these components through valve 8 into the top of column 10.

Heating pot 9 is charged with the selected ketone or nitroparaffin, and by utilizing any suitable standard source of heat the ketone or nitroparaffin is vigorously refluxed in column 10 while the formaldehyde and alkaline catalyst solution is metered into the top of the column using metering valve 7 as the regulator for rate of introduction. Column 10 is operated below its flood point, and condenser 11 prevents vapor losses. Through

the rectifying action of the column the monomethylol condensation product returns to heating pot 9, which is maintained at a pH below 7 by addition of the acid solution from tank 4. The product may be purified by flash distillation of the excess reactants, followed by fractional reduced pressure distillation of the residual monomethylol condensation product. It is desirable in the purification to effect a preliminary separation of the product and excess reactants, as by 10 flash distillation, to prevent undue heating of the former and consequent possible decomposition, although the total crude reaction product may be immediately subjected to reduced pressure distillation with satisfactory results.

Figure 2 represents apparatus for the continuous production of the monomethylol condensation products. The process described in connection with Figure 1 is duplicated up to the point of collection of the product in pot 9. In the continuous process the product is continuously withdrawn from pot 9 into storage tank 12, from which it is led into the center section of distillation column 13. In the latter the excess reactants are flashed off, condensed by condenser 14 and returned to the condensation reaction zone through recycle 15. The monomethylol product passes from the bottom of column 13 into storage 16, from which it may be withdrawn for the final fractional distillation under reduced pressure. In the continuous process additional ketone or nitroparaffin is charged into the top of column 10 to replace reaction loss.

The apparatus may be further modified in order that the alkaline catalyst solution contained in storage tank 1 may be blended with certain of the ketones or nitroparaffins stored in tank 3. In this case tank 3 has two outlets, one going directly to pot 9 for charging purposes. The other outlet passes through the system represented by 5, 6 and 7. When the catalyst is added by this means, the formaldehyde is passed through metering valve 8 directly into column 10.

The general embodiments of this invention having been outlined, the following examples constitute specific illustrations. All parts are based on parts by weight.

Example I

The apparatus used in this example was essentially that shown in Figure 1. A batch procedure was carried out and the catalyst added in conjunction with the ketone. Column 10 was a packed column of sufficient size to permit a ratio of methyl ethyl ketone to formaldehyde of at least 30 to 1 in the reaction zone at the top of the column. Heating pot 9 was charged with 72 parts of methyl ethyl ketone and 5.2 parts of 10% citric acid solution, the charge then being heated to 73.5° C., the boiling point of the water-methyl ethyl ketone azeotrope. By properly adjusting the pot temperature (73.5° to 95° C.) and the temperature of the column the latter was operated at high reflux but below its flood point. Through metered valves 7 and 8 over a period of four hours there then were added simultaneously 72 parts of methyl ethyl ketone containing 2.2 parts of 10% sodium hydroxide solution, and 85 parts of 35% Formalin, the latter having a pH of 3.8.

Following the reaction period the fractionating column was washed with 100 parts of distilled water and the washings were combined with the crude reaction mass. The combined mixture

then was distilled in vacuo through a packed distillation column. After a forerun of water and unreacted methyl ethyl ketone there was collected 93 parts (91% based on formaldehyde) of 2-methyl-3-ketobutanol, boiling at 90-93° C. under a pressure of 20 mm. of mercury. The ketobutanol had a refractive index of 1.4320 at 20° C.

Example II

The apparatus used in this example was that shown in Figure 2. The fractionating column 10 was a packed column which permitted a ratio of methyl ethyl ketone to formaldehyde of at least 30 to 1 in the reaction zone at the top of the column. Heating pot 9 was charged with 108 parts of methyl ethyl ketone and 10.4 parts of 10% citric acid solution, the charge then being heated to 73.5° C., the boiling point of the water-methyl ethyl ketone azeotrope. By properly adjusting the pot temperature (73.5° to 95° C.) and the temperature of the column, the latter was operated at high reflux but below its flood point. Through valve 7 over a period of 90 minutes there was added 81 parts of 37% Formalin, adjusted to a pH of 10.5 with aqueous sodium hydroxide.

Through valves 7 and 8 during the next five hours there were added simultaneously 284 parts of 37% Formalin at a pH of 10.5 and 378 parts of methyl ethyl ketone. Throughout this time the crude reaction mixture contained in heating pot 9 and consisting of methyl ethyl ketone, water and 2-methyl-3-ketobutanol was drawn off into storage tank 12 at a rate proportional to the rate of addition of the reactants. Also, during this time the pH of the mixture in the pot was maintained at 4.6-5.1 by adding small quantities of 10% citric acid solution from storage tank 4.

The crude reaction mixture (pH of 5.0) was continuously transferred from storage 12 to column 13, in which flash distillation removed 558 parts total of water and excess methyl ethyl ketone, the latter on condensation in condenser 14 being returned by recycle 15 to the reaction zone. The 2-methyl-3-ketobutanol was drawn from the bottom of column 13 into storage 16, from which it finally was withdrawn and distilled in vacuo. There was obtained 397 parts (86% based on formaldehyde) of 2-methyl-3-ketobutanol, boiling at 92°-95° C. under a pressure of 20 mm. of mercury.

Example III

The apparatus used in this example was essentially that shown in Figure 1. Column 10 was a packed column which permitted a ratio of methyl ethyl ketone to formaldehyde of at least 30 to 1 in the reaction zone at the top of the column. Pot 9 was charged with 5400 parts of methyl ethyl ketone and 3 parts of citric acid in the form of monohydrate crystals. The column and pot temperatures were adjusted so that the column operated under high reflux but below its flood point, and over a period of 35 hours there was added 3130 parts of 36% Formalin, adjusted to a pH of 10.5 with aqueous sodium hydroxide, through metering valve 7. The excess ketone then was stripped off in column 10, and in this manner 3100 parts of unreacted ketone was recovered.

The aqueous pot residue then was distilled under reduced pressure to remove the water. Finally, by further distillation under reduced pressure 3360 parts (88% based on formalde-

hyde) of 2-methyl-3-ketobutanol, boiling at 90°-93° C. under a pressure of 20 mm. of mercury was obtained.

Example IV

The apparatus used in this example was that shown in Figure 1. The fractionating column 10 was a packed column of sufficient size to permit a ratio of acetone to formaldehyde of at least 55 to 1 in the reaction zone at the top of the column. Heating pot 9 was charged with 174 parts of acetone and 5.2 parts of 10% citric acid solution. The column was adjusted to operate under high reflux but below the column flood point. The temperature varied from 56.3° to 85° C. in the heating pot as the reaction progressed. Through valve 7 during a period of 2.5 hours there was added 83.5 parts of 36% Formalin, adjusted to a pH of 10.2 with aqueous sodium hydroxide.

The reaction mixture was distilled under reduced pressure to remove the excess acetone and water. Subsequent fractionation of the residue in a packed fractionating column gave 13.3 parts of diacetone alcohol, boiling at 62°-68° C. under a pressure of 12 mm. of mercury and having a refractive index of 1.4235 at 20° C., and 74.1 parts (84% based on formaldehyde) of 3-ketobutanol, boiling at 73°-76° C. under a pressure of 12 mm. of mercury and having a refractive index of 1.4290 at 20° C.

Example V

The apparatus used in this example was that shown in Figure 1. Pot 9 was charged with 430 parts of diethyl ketone and 0.5 part of citric acid in the form of monohydrate crystals. Column 10 was a packed column adjusted to operate under rapid reflux but below its flood point, and over a period of five hours there was added 100 parts of 36% Formalin, adjusted to a pH of 10.5 with aqueous sodium hydroxide, through valve 7. After all the formaldehyde had been added the crude reaction mixture was adjusted to a pH of 7 with 10% citric acid solution from storage 4 and most of the excess diethyl ketone distilled off at atmospheric pressure. Fractional distillation was then effected under a pressure of 30 mm. of mercury, resulting in the collection of 105 parts (75% based on formaldehyde) of 2-methyl-3-ketopentanol, boiling at 109°-111° C.

Example VI

The apparatus used in this example was the same as that in the preceding example. The internal pressure of column 10, however, was maintained at 120 mm. of mercury and under these conditions the nitromethane utilized in this example boiled at 52° C. Heating pot 9 was charged with 183 parts of nitromethane and 5.2 parts of 10% citric acid solution, and the column was adjusted to operate under high reflux but below the column flood point. The temperature varied from 52° to 80° C. in the heating pot as the reaction progressed. Through valve 7 during 2.5 hours there was added 81 parts of 36% Formalin, adjusted to a pH of 10.0 with aqueous sodium hydroxide. Upon completion of the condensation the reaction mixture was neutralized to a pH of 7.0 with 10% citric acid solution and then distilled under reduced pressure. After a forerun of nitromethane and water there was collected 58.6 parts (64% based on formaldehyde) of 2-nitroethanol, boiling at 95°-99° C. under a pressure of 8 mm. of mercury.

Although the examples have shown the condensation as applied to acetone, methyl ethyl ketone, diethyl ketone and nitromethane, various other aliphatic ketones and nitroparaffins may be utilized in the process of this invention. Additional ketones include methyl isopropyl ketone, methyl propyl ketone, methyl n-butyl ketone, methyl isobutyl ketone, ethyl propyl ketone, ethyl isopropyl ketone, and the like. 10 Nitroethane, nitropropane, 1-nitrobutane, 2-nitrobutane and the like are additional nitroparaffins which are operable. The ketones and nitroparaffins should be liquids having moderately low boiling points, preferably not more than about 130° C., although higher boiling compounds may be used according to the process of this invention. As illustrated by Example VI it may be desirable to lower the boiling point of normally high boiling compounds by reducing 15 the pressure within the fractionating column. It is apparent that pressures lower than that shown in Example VI may be used, depending on the compound involved. Higher pressures also may be utilized, even above atmospheric, if the nature of the contemplated reaction so requires.

When operating the process according to the procedure shown in the examples, namely, using an aqueous formaldehyde solution, it is preferable that the aliphatic ketone or the nitroparaffin 20 have a boiling point lower than that of water or form an azeotropic mixture with water which is rich in the ketone or nitroparaffin. These conditions are desirable since they insure thorough reaction of the ketone or nitroparaffin with the aqueous formaldehyde solution at the top of the column. It is not necessary, however, that such conditions be followed, since the formaldehyde may be dissolved in a solvent other than water, in which case it is not necessary to take 25 into account the boiling point limitation imposed by the presence of water in the reaction mixture.

The examples have shown the use of formaldehyde in the form of an aqueous solution but, as has been indicated, the formaldehyde 30 may be added in solution in other solvents which are unreactive in the condensation reactions. Either monomeric formaldehyde or its polymers may be utilized in accordance with this invention.

50 Sodium hydroxide has been shown as the alkaline catalyst in all of the examples, but potassium hydroxide, sodium carbonate, potassium carbonate, sodium ethylate and the like also may be utilized. Other catalysts having sufficient alkalinity and solubility in the reaction medium are operable. The concentration of the alkaline catalyst solution is preferably about 10%, but the concentration may range from about 5 to about 15%.

60 One of the factors which governs the yield of the monomethylol compound obtained is the pH of the catalyst-containing solution added to the refluxing ketone or nitroparaffin. Generally speaking, high yields may be obtained when the pH of the solution containing the formaldehyde and the alkaline catalyst is between about 9 and about 11. In the case of the condensation of formaldehyde with acetone the pH preferably is between about 9 and about 10.5 and a range of 65 about 10 to about 10.5 is particularly applicable. In the condensation of formaldehyde and methyl ethyl ketone the preferable pH range is from about 10 to about 11 and about 10.5 to about 11 is most desirable. For the sake of convenience 70 the proper pH is most conveniently obtained by 75

dissolving the alkaline catalyst in the aqueous formaldehyde solution, but, as shown in Example I, the catalyst may be added in solution with the ketone providing the catalyst does not cause the ketone to condense with itself. Generally speaking 1.7 parts of 10% sodium hydroxide solution will bring 81 parts of 36% Formalin to a pH of 10.2 and 2.2 parts of 10% sodium hydroxide will give 81 parts of 36% Formalin a pH of 10.5. All pH measurements were made with a Beckmann 10 pH Meter, Industrial Model, utilizing a glass electrode adapted for use with alkaline solutions.

All of the examples have shown the use of citric acid to neutralize any of the basic catalyst which reaches the reaction pot. The citric acid may be utilized either in the form of a solution or as the crystalline material. Preferably some of the acid initially is charged into the reaction pot, and further additions made as they are needed during course of the condensation. The purpose of this neutralization is to prevent further condensation of the monomethylol products with any formaldehyde reaching the pot, and to hinder the dimerization of ketones when they are reactants. Acidic materials other than citric acid may be used for this purpose providing they have no deleterious effect, such as dehydration, on the monomethylol condensation products. Preferably they also should be nonvolatile. Sodium bisulfate, for example, may be used in place of citric acid. The concentration of the acidic material preferably is about 10%, but the range may extend from about 5% to about 15%.

One of the most desirable features of the process of this invention is that fact that it provides a means of having an excess of the ketone or nitroparaffin in the main reaction zone at the top of the column while continuously providing for the removal of the monomethylol substitution product. There is a certain desirable minimum excess of each ketone and nitroparaffin, as compared to formaldehyde, which will result in the formation of an optimum yield of the corresponding monomethylol product, and this excess is controlled by the rate of addition of the formaldehyde. It is apparent, however, that the ratio of ketone or nitroparaffin to formaldehyde will also depend to some extent upon the size of the reaction column used. Generally, the length of the column should be at least about six times its diameter, although longer columns are satisfactory. In the condensation of methyl ethyl ketone with formaldehyde the latter should preferably be added at such a rate that the ratio of methyl ethyl ketone to formaldehyde is at least 30 to 1 in the main reaction zone at the top of the column. With acetone the acetone to formaldehyde ratio should be at least 55 to 1 in this reaction zone. The acetone to formaldehyde ratio is approximately twice the methyl ethyl ketone to formaldehyde ratio because acetone has six active hydrogens equally able to react with formaldehyde, whereas methyl ethyl ketone only has two. Furthermore, the monosubstitution product of acetone still has two active hydrogens on the methylene group adjacent to the carbonyl group, while the monosubstitution product of methyl ethyl ketone has only one. In other words, it is apparent that the number and relative activity of the active hydrogen atoms in the ketone or nitroparaffin determines to some extent the excess of these compounds which is required.

Fractionating column 10 may be a packed, bubble-plate, baffle-plate or like fractionating column. A packed column may contain various

5 packings, but should adhere to certain specifications in size. On a laboratory scale the column may be packed with glass beads, glass or stainless steel helices, etc., but a commercial column will preferably employ Raschig rings made of glass, porcelain or some other material not corroded by the reactants. Distillation column 13 may be similarly packed. The reaction column 10 should have a length at least about six times the diameter in order to provide sufficient volume to permit the desired excess of ketone or nitroparaffin as compared to formaldehyde, but longer columns are operable and usually are actually used. The column may be electrically heated, and in this manner the temperature controlled very accurately so that the column operates below its flood point for each particular ketone or nitroparaffin. Steam, superheated steam, oil and Dowtherm may be utilized, however, for heating the column. The same heating media may be used in connection with heating pot 9.

In packed columns the gas and liquid velocities for countercurrent operation are limited by the tendency of the column to flood at high rates of either gas or liquid. As either gas or liquid velocity is gradually increased, the liquid holdup in the packing is increased, and a point is finally reached where the pressure drop rises sharply with even a slight increase in gas velocity. Entrainment of liquid in the gas leaving the tower also increases sharply. This point is called the flood point. In the process in accordance with this invention it would not be desirable to operate at or above the flood point, because of loss of material and decreased rectification, but by operating below the flood point a large excess of the ketone or nitroparaffin in the reaction zone is insured while at the same time it is possible for the column to remove the monomethylol substitution product as it is formed. By the latter action the monomethylol compound is prevented from remaining in the region of highest formaldehyde concentration. Even though the formaldehyde concentration at its highest is slight in comparison to the amount of ketone or nitroparaffin present, nevertheless continuous removal of the monomethylol condensation product prevents further condensation of the latter with additional formaldehyde and constitutes one of the basic advantages of the process.

In case it is desirable to convert the monomethylol substitution products to the corresponding vinyl compounds this may be accomplished by adding the monomethylol product dropwise to a reaction pot containing a dehydration catalyst and an excess of water at its boiling point. In the case of 3-ketobutanol and 2-methyl-3-ketobutanol, for instance, these ketone alcohols undergo a molecular splitting out of water to form the corresponding vinyl ketones, methyl vinyl ketone and methyl isopropenyl ketone, respectively, which may be distilled in the form of their azeotropes with water through a fractionating column attached to the reaction pot. The methyl vinyl ketone-water azeotrope is homogeneous, whereas the corresponding azeotrope of methyl isopropenyl ketone is not. The latter separates into two layers on cooling, consequently it is possible by use of an automatic separator to return the water layer to the distillation flask.

Iodine is an efficient dehydration catalyst, but other catalysts which are operable include ortho-phosphoric, sulfuric, hydrochloric, oxalic, p-toluenesulfonic, and β -naphthalenesulfonic acids. In the case of sulfuric acid, it is desirable con-

currently to use an inhibitor such as sulfur, hydroquinone, or tert-butyl catechol. Both methyl vinyl ketone and methyl isopropenyl ketone may be purified by redistillation. The former, being miscible with water in all proportions, may be redistilled in the form of its azeotrope, which contains about 7-8% water. The anhydrous ketone then may be prepared by removing the last traces of water by physical means, such as freezing or azeotropic distillation with a third component. Methyl isopropenyl ketone may be dried by simple distillation or by freezing out the excess water.

The process in accordance with this invention provides for a very large excess of the ketone or nitroparaffin in the reaction zone at the top of the reaction column and for the continuous removal of the monomethylol reaction product from the reaction zone. Because of the latter effect an improvement is obtained over prior art processes which utilize large excesses of the ketone or nitroparaffin but which do not prevent further condensation. The process also is advantageous in that the formation of ketone dimerization products such as diacetone alcohol is hindered by reversal of the equilibrium between the ketone and its dimer at some point lower in the reaction column. The equilibrium is reversed in favor of ketone formation, thereby preventing accumulation of the dimer as a by-product. This is particularly true when the dimerization reversal is more rapid than the formaldehyde-ketone condensation. The process also is advantageous in that it provides a means of neutralizing the alkaline catalysts in such a manner that the latter will not catalyze condensations which are not desired.

The yields of monomethylol substitution products obtained in accordance with this invention are superior to those obtained utilizing only the principles of high dilution. Numerically speaking a yield of about 70 to about 90% of 2-methyl-3-ketobutanol actually is obtained as compared with the 68% which is claimed by prior art processes. Similarly, 3-ketobutanol is obtained in yields of about 70 to about 85% as compared with the 27% lately shown to be the maximum using prior art procedures. Because the mono-substitution products are obtained to the virtual exclusion of undesirable secondary reaction products, the process is not encumbered by purification problems. Furthermore, although within the reaction zone at the top of the column the ratio of ketone or nitroparaffin to formaldehyde is high, in the overall reaction the ratio of the total amount of ketone or nitroparaffin to the total amount of formaldehyde used is quite low. In this respect the ratio of methyl ethyl ketone to formaldehyde may be as low as about 1.5 to 1 as compared with the 4 to 1 ratio required by previous procedures. Similarly, an acetone to formaldehyde ratio of about 2 to 1 may be utilized as compared to 4 to 1 by other methods, and a nitromethane to formaldehyde ratio of about 3 to 1 is possible as compared to the 10 to 1 required by the prior art.

The process of this invention therefore requires less ketone or nitroparaffin than do previous processes, yet makes possible attainment of desirable high ratios of these compounds to formaldehyde in the reaction zone at the top of the reaction column. The commercial advantages of the process are immediately apparent. Outstanding yields of the monomethylol condensation products are obtained, and operational costs are

markedly reduced. In the latter regard the use of relatively small amounts of ketone or nitroparaffin in comparison to formaldehyde, and the necessity for recovering only small amounts of excess ketone or nitroparaffin upon completion of the condensation reaction are of prime importance.

The monomethylol compounds obtained in accordance with this invention are useful as solvents for cellulose derivatives and in the preparation of lacquers. The corresponding vinyl compounds, such as methyl vinyl ketone and methyl isopropenyl ketone, derived from the monomethylol compounds may be polymerized

- 5 either alone or in conjunction with other polymerizable compounds to obtain highly useful polymeric materials.

The term "fractionator," as used in the claims attached hereto, is used to mean either the combination of a fractionating column with a separate heating pot as shown in Fig. 1 and Fig. 2 hereof or the type of fractionating apparatus commonly used commercially which consists of a fractionating column so constructed that the

- 25 bottom portion thereof serves as a heating pot.

What I claim and desire to protect by Letters Patent is:

1. The process of condensing formaldehyde with a liquid organic compound selected from the 30 group consisting of saturated unsubstituted primary and secondary nitroparaffins and saturated unsubstituted aliphatic ketones which have at least one hydrogen atom united with a carbon atom alpha to the carbonyl group to provide a monomethylol derivative of said organic compound, which process comprises introducing said organic compound into a fractionator, applying heat at the bottom portion of said fractionator to vaporize said organic compound, passing the 35 evolved vapors upwardly through the fractionator, said fractionator being operated under total reflux conditions but below the flood point of the fractionator, flowing formaldehyde and an alkaline catalyst downwardly through the fractionator and countercurrent to the upwardly flowing vapors of the organic compound, maintaining said fractionator at a temperature to cause said organic compound to react with said formaldehyde to form a monomethylol derivative of said organic compound, simultaneously rectifying the mixture of reactants and monomethylol derivative in the said fractionator to provide a progressively higher concentration of the monomethylol derivative downwardly through 45 the fractionator, and withdrawing said monomethylol derivative from the bottom portion of said fractionator, the rate of flow of said formaldehyde being such that there is an excess of said organic compound on a molar basis within the reaction zone of the fractionator.

2. The process of condensing formaldehyde with a liquid organic compound selected from the group consisting of saturated unsubstituted primary and secondary nitroparaffins and saturated unsubstituted aliphatic ketones which have at least one hydrogen atom united with a carbon atom alpha to the carbonyl group to provide a monomethylol derivative of said organic compound, which process comprises introducing said 55 organic compound into a fractionator, applying heat at the bottom portion of said fractionator to vaporize said organic compound, passing the evolved vapors upwardly through the fractionator, said fractionator being operated under total reflux conditions but below the flood point of

the fractionator; flowing aqueous formaldehyde and an alkaline catalyst downwardly through the fractionator and countercurrent to the upwardly flowing vapors of the organic compound, maintaining said fractionator at a temperature to cause said organic compound to react with said formaldehyde to form a monomethylol derivative of said organic compound, simultaneously rectifying the mixture of reactants and monomethylol derivative in the said fractionator to provide a progressively higher concentration of the monomethylol derivative downwardly through the fractionator, and withdrawing said monomethylol derivative from the bottom portion of said fractionator, the rate of flow of said formaldehyde being such that there is an excess of said organic compound on a molar basis within the reaction zone of the fractionator.

3. The process of claim 2 wherein a saturated unsubstituted aliphatic ketone having at least one hydrogen atom united with a carbon atom alpha to the carbonyl group is employed as the liquid organic compound.

4. The process of claim 3 wherein methyl ethyl ketone is employed as the saturated unsubstituted aliphatic ketone.

5. The process of claim 4 wherein a mixture of aqueous formaldehyde and an alkaline catalyst having a pH between about 9 and about 11 is flowed downwardly through the fractionator.

6. The process of claim 5 wherein the rate of flow of the mixture of aqueous formaldehyde and alkaline catalyst is such that the molar ratio methyl ethyl ketone:formaldehyde within the reaction zone of the fractionator is at least 30:1.

7. The process of claim 3 wherein acetone is employed as the saturated unsubstituted aliphatic ketone.

8. The process of claim 7 wherein a mixture of aqueous formaldehyde and an alkaline catalyst having a pH between about 9 and about 11 is flowed downwardly through the fractionator.

9. The process of claim 8 wherein the rate of flow of the mixture of aqueous formaldehyde and alkaline catalyst is such that the molar ratio acetone:formaldehyde within the reaction zone of the fractionator is at least 55:1.

10. The process of claim 2 wherein the liquid organic compound employed is a saturated unsubstituted nitroparaffin having at least one hydrogen atom united with the carbon atom to which the nitro group is attached.

11. The process of claim 10 wherein the nitroparaffin employed is nitromethane.

12. The process of condensing formaldehyde with a liquid organic compound selected from the group consisting of saturated unsubstituted primary and secondary nitroparaffins and saturated unsubstituted aliphatic ketones which have at least one hydrogen atom united with a carbon atom alpha to the carbonyl group to provide a monomethylol derivative of said organic compound, which process comprises introducing said organic compound into a fractionator, applying heat at the bottom portion of said fractionator to vaporize said organic compound, passing the evolved vapors upwardly through the fractionator, said fractionator being operated under total reflux conditions but below the flood point of the fractionator, flowing formaldehyde and an alkaline catalyst downwardly through the frac-

tionator and countercurrent to the upwardly flowing vapors of the organic compound, maintaining said fractionator at a temperature to cause said organic compound to react with said formaldehyde to form a monomethylol derivative of said organic compound, simultaneously rectifying the mixture of reactants and monomethylol derivative in the said fractionator to provide a progressively higher concentration of the monomethylol derivative downwardly through the fractionator, neutralizing in the bottom portion of said fractionator any alkaline catalyst present, and withdrawing said monomethylol derivative from the bottom portion of said fractionator, the rate of flow of said formaldehyde being such that there is an excess of said organic compound on a molar basis within the reaction zone of the fractionator.

13. The process of condensing formaldehyde with a liquid organic compound selected from the group consisting of saturated unsubstituted primary and secondary nitroparaffins and saturated unsubstituted aliphatic ketones which have at least one hydrogen atom united with a carbon atom alpha to the carbonyl group to provide a monomethylol derivative of said organic compound, which process comprises introducing said organic compound into a fractionator, applying heat at the bottom portion of said fractionator to vaporize said organic compound, passing the evolved vapors upwardly through the fractionator, said fractionator being operated under total reflux conditions but below the flood point of the fractionator, flowing a mixture of aqueous formaldehyde and an alkaline catalyst at a pH between about 9 and about 11 downwardly through the fractionator and countercurrent to the upwardly flowing vapors of the organic compound, maintaining said fractionator at a temperature to cause said organic compound to react with said formaldehyde to form a monomethylol derivative of said organic compound, simultaneously rectifying the mixture of reactants and monomethylol derivative in the said fractionator to provide a progressively higher concentration of the monomethylol derivative downwardly through the fractionator, and withdrawing said monomethylol derivative from the bottom portion of said fractionator, the rate of flow of said formaldehyde being such that there is an excess of said organic compound on a molar basis within the reaction zone of the fractionator.
